UNITED STATES PATENT OFFICE.

HARVEY C. HAYES, OF WASHINGTON, DISTRICT OF COLUMBIA.

METHOD AND APPARATUS FOR TRANSMITTING AND REPRODUCING SOUNDS.

Application filed July 7, 1923. Serial No. 650,183.

My invention relates broadly to sound transmitters and reproducers, and more particularly to a method and apparatus for transmitting or reproducing sound free of resonance effects and inherent distortion of the sound.

One of the objects of my invention is to provide a method of damping the diaphragm of a sound transmitter or reproducer where-
10 by energy can be absorbed from the dia-
phragm at any desired point or points and
which can be made particularly effective for
absorbing the energy corresponding to any
15 particular frequency at which the dia-
phragm is desired to be non-resonant.

Another object of the invention is to pro-
vide a construction of damping device for a
diaphragm of a sound reproducer whereby
the articulation of the reproduced sound is
20 considerably improved as compared with
sound reproducers heretofore available.

A further object of the invention is to pro-
vide a simple construction of damping means for
25 diaphragms whereby distortion due to the tendency of the diaphragm to
vibrate at its fundamental or at its har-
monics is eliminated.

My invention finds particular applica-
30 tion to sound transmitters and reproducers
employed in telephone circuits and in radio
circuits either as a control for a radio trans-
mission system or as a loud speaker at a
radio receiver, but the principle may also
35 be employed in connection with phonograph
diaphragms and other acoustic devices.

The invention will be more clearly under-
stood by reference to the accompanying
drawings in which: Figure 1 is a theoreti-
cal diaphragm used in explaining the method
employed in my invention; Fig. 2 is a theo-
retical curve for use in explaining the prin-
ciple of the diagram in Fig. 1; Fig. 3 is a
side elevation partially broken away and in
section to the application of my invention to
a telephone reproducer or loud speaker; Fig.
4 is a plan view of the baffle plate of my
invention, with the diaphragm removed and
the cap member shown in section on line
4-4 of Fig. 3; Fig. 5 is a side view of the
baffle plate and one form of support there-
for partially in section; and Fig. 6 is a
fragmentary view of the reproducer showing

one form of adjusting means for moving
the baffle plate relative to the diaphragm
or rendering the different portions of the 55
diaphragm non-resonant to undesired fre-
quencies.

The quality of sound reproduced by dia-
phragms stimulated to vibrate by electrical
means, as in the telephone, or by mechanical 60
means, as in the graphophone, is usually
distorted to some extent because the dia-
phragm is always resonant at certain fre-
quencies, the lowest of which is termed its
fundamental, and higher frequencies of 65
which are termed its harmonics. The sound
energy radiated from the diaphragm is much
greater in proportion at the resonant than
at other frequencies and there is a tendency
for the diaphragm to continue vibrating 70
longer at these frequencies after the driving
force has ceased than it does at other fre-
quencies. This may result in distorting the
reproduced sound to something quite dif-
ferent from the original providing the orig- 75
inal sound includes any of the resonant fre-
quencies. Moreover, the same distortion
factors are usually present at both transmit-
ting or recording end, for the diaphragm of
the microphone used to transform the sound 80
energy into electrical energy and the dia-
phragm that serves for driving the stylus in
the recording mechanism for making graph-
ophone records each have certain, definite
85 frequencies at which they are resonant.

The location of the nodes and loops that
may be present in a diaphragm geometrical-
ly shaped actuated by a simple harmonic
force applied at its center are known, as is
also the relation of the pitchy resulting 90
from each mode of vibration, to the funda-
mental; and in case of any vibrating dia-
phragm this information can be obtained ex-
perimentally. An analysis of the sound
emitted by a diaphragm driven at any fre-
95 quency shows what harmonics are present
and their relative intensity. This data to-
gether with a knowledge of the possible
forms in which the diaphragm may vibrate
and the frequency of each mode of vibra- 100
tion, serves to localize on the diaphragm the
areas that are unduly resonant and therefore
responsible for the major part of the distor-
tion. By my present invention, I provide

means for absorbing energy from these regions on the diaphragm in such a way as to prevent it from being radiated as sound and accordingly a more faithful reproduction of the original sound results because of the removal of the distorting elements.

The principle involved in the present method may be understood from a consideration of Fig. 1 which represents a cylinder 10 1 fitted with an air-tight but frictionless theoretical piston 2, and closed at one end by a head 3 except for an opening 4 which can be varied in cross-section from zero to the whole cross-section of the cylinder. For 15 the purpose of illustration, assume that the opening 4 is in the form of the well known camera lens diaphragm whose exposed or open area is concentrically varied at will. Suppose now the vent 4 be closed and the 20 piston pushed back and forth across its position of equilibrium. If the thermodynamic cycle through which the air in the pump chamber passes be considered adiabatic, that is where:

25

$$PV = \text{Constant}$$

as represented by the theoretical curve in Fig. 2 where P represents pressure and V the volume as it would be practically if the 30 frequency of the piston were of the order of the pitch of ordinary audible sound, then the sum total of the work done on the piston by the gas in the cylinder or by the piston on the gas in the cylinder will be zero and 35 independent of the frequency. If, however, a small opening were made in the vent 4 some of the air in the cylinder would escape on the instroke and some would return during the outstroke and in order to keep the 40 piston moving with the same amplitude and frequency as much energy must be supplied to it as is used up in driving air back and forth through the vent. It can also be shown that the amount of energy that the 45 cylinder chamber absorbs from the piston is dependent upon both the frequency of motion of the piston and the cross-section of vent 4. It can also be shown that if the vent 4 be made up of several small holes 50 instead of one large one the energy absorbed from the piston by the chamber will leave the chamber almost wholly as heat, but that if one or more large holes are used a considerable amount of energy will radiate 55 through as sound.

Suppose now the frequency of the piston be changed continuously increasing from a frequency that is very low and that the 60 energy input into the piston be kept constant. Sound energy would radiate at all time from the open end of the vent but some frequency would eventually be met where the inertia of the piston and the restoring force introduced by the air-tight chamber 65 will be such as to make the natural period

of vibration of the piston of equal value. Under such conditions, the sound input from the open end of the cylinder will have an intensity considerably greater in proportion than it does for other frequencies. 70 If, now, the vent 4 be opened a proper amount, although it is preferable to use several small vents, energy may be absorbed from the piston by the chamber to such an extent that the sound radiated at this frequency is much less out of proportion with respect to that radiated at other frequencies. 75

In case of a vibrating telephone diaphragm or other similar sound reproducing diaphragm such as 5 in Fig. 3, any small portion may be regarded as a piston, and if a baffle plate 6 is placed parallel with and very close to the diaphragm 5 the corresponding area of this plate on the side adjacent the diaphragm may be regarded as 80

the closed end of the cylinder referred to in Fig. 1. The cylinder needs no sides, although they are provided at the extremity of the diaphragm by the casing as will be hereinafter described, for the narrowness of 85

the crevice 7 between the diaphragm 5 and the baffle 6 prevents the air from moving readily in this direction. And, of course, the air will find difficulty in moving outward from the small cylinder described because 90

of the pressures already established by the moving diaphragm. Therefore, any small hole 8 or holes 9, 10, 11, or 12 made to perforate the baffle plate 6 within the area represented as the end of the small cylinder will 95

absorb energy from the piston area of the diaphragm 5. In other words, a small hole through the baffle plate at any point will 100

absorb energy from a small area of the diaphragm opposite to the hole and closely 105

adjacent thereto, and therefore the disturbing resonance frequencies of a diaphragm can be ironed out, or in other words damped 110

out by first determining to what mode of harmonic vibration they are due and then by placing a proper number of small holes or apertures through that portion of the baffle plate that covers the vibrating loops. 115

The diaphragm 5 can be driven as a loud speaker by means of electromagnet 14 connected in any voice frequency circuit as, for example, the output circuit of electron tube 15, the input circuit of which is supplied from a suitable circuit 16 subjected to the 120

voice modulations. The baffle plate 6 is apertured at 17 to enable the electromagnet 14 to have its pole faces positioned immediately adjacent the diaphragm 5. The baffle plate 6 is mounted in a frame 18 by means 125

of screws 19 radially positioned at proper points about the periphery of the frame 18. The frame is provided with fine pitched threads 20 which cooperate with internal threads 21 within the housing 23 of the 130

electromagnet. The diaphragm 5 is securely

8 mounted on the periphery of the magnet housing 23, and gasket 24 located about the edge of the diaphragm whereby cap member 25 threaded at 26 will seat against the gasket and securely hold the diaphragm in position. The baffle plate may be adjusted in position relative to the diaphragm by any suitable means. I have shown the frame 18 provided with a plurality of sockets 27 radially positioned about the periphery of the screw threaded frame. An elongated slot 28 is provided in the wall of the magnet housing 23, and a corresponding slot 29 is formed in the cap member. After the baffle plate 6 is 10 assembled in position relative to diaphragm 5 it may be accurately adjusted by means of key 30, having one end fitted into some one of the sockets 27 and the baffle plate moved in a peripheral direction to adjust the 15 distance between the baffle plate and the diaphragm.

10 It will be understood that the details of the construction herein described are not intended as limitations upon the invention, but 25 merely as an illustration of one form which my invention may take. As heretofore set forth, the apertures 8, 9, 10, 11 and 12 are located in the baffle plate at those positions where it is determined for a particular dia- 30 phragm that undesired resonance effects should be eliminated.

35 It will be understood that I intend no limitations upon the present method and apparatus other than are imposed upon the scope of the appended claims.

Having thus described my invention, what I claim and desire to secure by Letters Patent of the United States is as follows:

1. The method of damping the diaphragm 40 of a sound reproducing device, consisting in absorbing energy from the diaphragm from a side opposite to the principal sound delivery side of said diaphragm at any desired point or points corresponding to any particular frequency for which it is desired that 45 said diaphragm be non-resonant.

2. The method of damping the diaphragm 50 of a sound transmitter or reproducer, which consists in absorbing from the diaphragm from a side opposite the sound impressing or delivery side of said diaphragm at a plurality of points throughout the area thereof those frequencies for which the diaphragm is desired to be rendered non-resonant.

55 3. The method of damping the diaphragm of a sound transmitter or reproducer, which consists in absorbing from different separated points on said diaphragm from a side opposite the sound impressing or delivery side thereof those frequencies for which it is desired that said diaphragm be rendered non-resonant.

4. In a sound transmitter or reproducer, 60 the combination of a diaphragm, means positioned adjacent said diaphragm at the side

opposite the sound impressing or delivery side thereof and extending in a plane substantially throughout the area of said diaphragm for rendering said diaphragm non-resonant to particular frequencies. 70

5. In a sound transmitter or reproducer, the combination of a diaphragm, means located directly adjacent said diaphragm at a side opposite the sound impressing or delivery side thereof in a plane substantially 75 throughout the area of said diaphragm for damping said diaphragm at particular points throughout said area for rendering said diaphragm non-resonant to particular frequencies. 80

6. A sound transmitter or reproducer, comprising in combination a diaphragm, an apertured baffle plate mounted adjacent said diaphragm at a side opposite the sound impressing or delivery side and located with 85 respect thereto whereby said diaphragm is rendered non-resonant for particular frequencies.

7. In a sound transmitter or reproducer, the combination with a diaphragm, means 90 for supporting said diaphragm, and a baffle plate located adjacent one side of said diaphragm opposite the sound impressing or delivery side thereof and supported by said means, said baffle plate having a substantial thickness being apertured at a plurality of points throughout its area for providing energy absorbing air columns for rendering said diaphragm non-resonant to particular 95 frequencies. 100

8. A sound transmitter and reproducer, comprising in combination a diaphragm, means for supporting said diaphragm, a baffle plate located immediately adjacent said diaphragm and supported by said means, said baffle plate having a substantial thickness and being apertured at a plurality of points throughout the area of said diaphragm for providing air columns for absorbing energy from different areas of said diaphragm, whereby disturbing resonance effects may be substantially eliminated, and means for adjusting the distance between said diaphragm and said baffle plate. 105 110

9. A sound transmitter and reproducer, comprising in combination a diaphragm, a support for said diaphragm, a baffle plate carried by said support, said baffle plate having a substantial thickness and apertured at a plurality of points throughout the area of said diaphragm for providing air columns for damping said diaphragm at different positions throughout its area for eliminating undesired resonance effects, a slot in said supporting means, and means passing through said slot and into said baffle plate for adjusting the distance between said baffle plate and said diaphragm. 115 120 125

10. A sound transmitter and reproducer, comprising in combination a diaphragm, a 130

support for said diaphragm, a baffle plate located adjacent said diaphragm and extending substantially throughout the area thereof, a screw threaded frame for carrying said baffle plate, said baffle plate having a substantial thickness and being apertured at a plurality of points throughout the area of said diaphragm for providing air columns for

absorbing energy from different portions of said diaphragm whereby said diaphragm is ¹⁰ rendered non-resonant to particular frequencies, and means secured to said frame on said baffle plate for adjusting the distance between said baffle plate and said diaphragm.

HARVEY C. HAYES.
